UNITED STATES PATENT OFFICE.

ALLAN D. SKINNER AND ROBERT C. STEVENS, OF ERIE, PENNSYLVANIA, ASSIGNEES
TO SKINNER ENGINE COMPANY, OF ERIE, PENNSYLVANIA, A CORPORATION.

STEAM-ENGINE VALVE.

1,119,462.

Specification of Letters Patent.

Patented Dec. 1, 1914.

Application filed September 11, 1914. Serial No. 861,203.

To all whom it may concern:

Be it known that we, ALLAN D. SKINNER and ROBERT C. STEVENS, citizens of the United States, residing at Erie, in the county of Erie and State of Pennsylvania, have invented certain new and useful Improvements in Steam-Engine Valves, of which the following is a specification.

This invention relates to steam engine valves, and especially to valves applicable to engines of the uniflow type, having a middle exhaust port, and auxiliary exhaust ports located between the middle port and the cylinder heads, and has for its object 15 to provide improved means for controlling the exhaust through the auxiliary ports.

When the engine is running condensing, vacuum tends to be produced in the cylinder during the return stroke of the piston, and 20 the auxiliary ports may cease to operate, but when the engine is running non-condensing, it is desirable to periodically open the auxiliary exhaust passages for the escape of steam after the expansion stroke. Therefore 25 the present invention is designed to provide improved means for holding the auxiliary valves, which control the auxiliary ports, closed when the engine is running condensing, and to permit the same to operate when the engine is running non-condensing, to avoid excessive compression, or 30 for other reasons, and in the present invention said valves are controlled by the presence and absence of vacuum in the exhaust pipe, as will more fully appear from the 35 following description.

In the accompanying drawings:—Figure 1 is a sectional view of one embodiment of the invention. Fig. 2 is a similar view of 40 a modification.

Referring especially to Fig. 1, the cylinder A, of the uniflow or uni-directional type, is provided with main exhaust ports B, located at or about the middle of the cylinder, and controlled by the piston indicated in dotted lines at X, in a manner common 45 in the art. The cylinder also has auxiliary exhaust ports C located between the main ports B and each cylinder head. A valve D, preferably single-seated, controls the passage from the ports C to the exhaust chamber Y which communicates with the exhaust pipe T leading to a condenser (not shown). The valve D is mounted on a stem

I, and is normally held open by a spring E. 55 A piston F is also mounted on the stem I, and moves in a small cylinder G. A port H communicates from the end of the cylinder A to the chamber G. The valve stem I extends through the wall of the exhaust casing or chamber and on its outer end is preferably provided with a plate J located within a casing or housing K, in which is mounted a toggle comprising a pin L, link M, bell crank N and a roller S carried by one end 60 of the bell crank and bearing against the plate J. To the other end of the bell crank is connected a piston O moving in a cylinder chamber P, and said piston is normally advanced by spring Q. From the head of 70 the chamber P, a pipe R extends to the main exhaust pipe T.

This device operates as follows: When the engine runs non-condensing, the piston X passes the ports B and the steam exhausts 75 through said ports in the usual manner. On the return stroke, compression would begin as soon as the piston had passed the ports B, but for the fact that the valve D is held open by the spring E, and the port C is 80 therefore opened so that the residual steam escapes through said port until the piston passes and closes the same. Compression then begins, and the pressure is communicated through the port H to the chamber G, 85 and when it exceeds the strength of the spring E the piston F is advanced and closes the valve D. The valve then remains closed during compression and during the succeeding admission and expansion periods, 90 until the pressure in the cylinders A and G has so dropped that the spring E causes the valve to open, as when the ports B are uncovered after expansion. During the above cycle, the toggle remains flexed, and the 95 roller S held away from the plate J on the end of the valve stem, by the action of the spring Q on the piston O. Now, if the engine runs condensing, the vacuum in the exhaust pipe T acts through the pipe R to 100 reduce the pressure behind the piston O, and said piston being retracted or moved inwardly by atmospheric pressure overcoming the spring Q straightens the toggle and the roller S acts against the plate J and the 105 valve stem and closes the valve D, and holds the same closed as long as sufficient vacuum exists. If the vacuum fails, the spring Q

acts to advance the piston O and releases the valve D, which then operates according to the non-condensing cycle above described.

In the modified form shown in Fig. 2, a reverse arrangement appears. In this, the valve D' opens inwardly, and its stem has a piston F' operating in a chamber G', the inner or upper end of which is connected by a passage H' with the end of the cylinder A. A spring E', under the piston F', tends to open the valve. A plate J' is attached to the outer end of the valve stem and a roller S carried by the toggle N' bears on the inner or upper side of the plate J', the toggle N' being connected to the piston O by a yoked rod V which spans the valve stem, the spring Q, and the connecting pipe R being arranged similarly to the form shown in Fig. 1. The operation is also similar, except that the valve D' is opened inwardly by the spring E', except when in consequence of excess pressure in the cylinder A acting through the passage H' the piston F' holds the valve closed; and when the engine is running condensing the toggle is actuated to hold the valve D' closed and inoperative.

It will be seen that the toggle mechanism acts as a positive locking mechanism for holding the valve shut when the engine is running condensing.

We claim:

1. In a valve mechanism for steam engines, the combination of an exhaust valve, a locking mechanism for said valve, and means actuated by reduction of pressure in the exhaust pipe of the engine for operating said mechanism to lock said valve in closed position.

2. The combination with a steam engine cylinder having main and auxiliary exhaust ports, of a valve controlling the auxiliary

exhaust port, a locking mechanism for said valve, and means actuated by reduction of pressure in the exhaust pipe for operating said mechanism to lock said valve in closed position.

3. The combination with a steam engine cylinder having main and auxiliary exhaust ports, of a valve controlling the auxiliary exhaust port and operative when the engine is running non-condensing, a locking mechanism for said valve, and means controlled by vacuum in the exhaust pipe for operating said locking mechanism to hold said valve closed when the engine is running condensing.

4. The combination with a steam engine cylinder having main and auxiliary exhaust ports, of a valve controlling the auxiliary port, a spring tending to open said valve, a lever operative to close said valve, a cylinder communicating with the exhaust pipe of the engine, and a piston in the last mentioned cylinder connected to the lever and adapted to be operated under reduction of pressure in the exhaust pipe, to hold said valve closed.

5. The combination with a steam engine cylinder having main and auxiliary exhaust ports, of a valve controlling the auxiliary port, a spring tending to open said valve, a toggle acting on the valve and adapted when straightened to lock the valve closed, and means actuated by reduction of pressure in the exhaust pipe of the engine to straighten the toggle.

In testimony whereof, we affix our signatures in presence of two witnesses.
